UNITED STATES PATENT OFFICE.

WILLIAM W. WORD, OF SAN FRANCISCO, CALIFORNIA.

HAMMER-CONTROLLING MEANS.

No. 840,033.

Specification of Letters Patent.

Patented Jan. 1, 1907.

Application filed October 4, 1906. Serial No 337,358.

To all whom it may concern:

Be it known that I, WILLIAM W. WORD, a citizen of the United States, residing in the city and county of San Francisco and State of California, have invented certain new and useful Improvements in Hammer-Controlling Means, of which the following is a specification.

My invention relates to the class of fluid-engine controls, and particularly to the class of controlling means or mechanism for fluid-engines which are directly connected to hammers for forging purposes.

The particular application of my invention is to machines for shaping and sharpening rock-drills in which plural motive engines actuated by air or steam are used, each engine being directly connected with and driving a hammer, the hammers being usually arranged in planes at right angles to each other. These machines are illustrated in several of my previous patents—as, for example, in No. 731,728, June 23, 1903, and No. 766,861, August 9, 1904, which said patents are mentioned merely for the purpose of showing the particular use and object of my present invention.

The immediate object of my present invention is to enable the operator to freely manipulate and attend to the forging work and processes that necessarily occupy his whole sight and both hands, leaving the hammer-action to be controlled by his foot alone, according to the requirements of the work.

My present invention may be briefly stated to consist in a fluid-operated means for separately and independently controlling the plural fluid-engines which drive the hammers, said control consisting in starting and stopping the engines, regulating the frequency and intensity of the blows of the hammers, and determining the position of the hammers when out of action.

Particularly my invention consists in the novel devices and their combinations, which I shall hereinafter fully describe by reference to the accompanying drawings, in which—

Figure 1 is a side elevation of a double forging-hammer of the type for which my controlling means is particularly intended, showing the application of my invention. Fig. 2 is a longitudinal section, enlarged, on line *y y* of Fig. 3 through the controlling

and valve chambers of the vertically-disposed hammer-operating engine, showing the parts in position to maintain said engine at rest. Fig. 3 is a cross-section on the line *x x* of Fig. 2. Fig. 4 is a perspective view of the control-valve. Fig. 5 is a top plan, enlarged, of the foot-controlled initial casing of the general fluid system. Fig. 6 is a longitudinal section of the same on the line *z z* of Fig. 5. Fig. 7 is a cross-section of the same on the line *w w* of Fig. 6. Fig. 8 is a side elevation of the rocking valve of the initial casing of Fig. 6. Fig. 9 is an end view of the same. Fig. 10 is a cross-section of the same on the line *v v* of Fig. 8. Fig. 11 is a perspective view of said valve.

In Fig. 1 of the drawings, 1 is a foundation, 2 is a supporting-frame, 3 is a pillar for a horizontally-disposed fluid-engine 4, and 5 is a post for a vertically-disposed fluid-engine 6. The engine 4 has a hammer 7, and the engine 6 has a hammer 8, which operates on an anvil 9. These parts represent a type of double hammer for forging or making and sharpening rock-drills, such a double hammer, for example, as is illustrated in my prior patents above referred to.

Describing first the vertically-disposed engine 6 and its control and referring for this purpose to Fig. 2, 10 is a valve-chamber in which is seated a slide-valve 11, which controls the ports 12 to the engine and the exhaust-port 13 in the ordinary manner. 14 is the control-chamber in which is seated the slide valve 15, which controls a passage 16, connecting the two chambers 10 and 14, as seen in Fig. 3. This valve, as shown in Figs. 3 and 4, is sector-shaped in section and is carried, as shown in Fig. 2, on a stem 17, the inner end of which carries a piston 18, and the outer end, passing through the chamber 14, has secured to its extremity a contact-arm 19. This arm bears upon the outer extremity of a slideable holding-pin 20, which passes into the valve-chamber 10 and impinges upon the near end of the valve 11 in said chamber. 21 represents cushions in the chamber 10 to limit the movement of the valve 11. In the control-valve 15, as shown in Figs. 4 and 3, is made a small port 15', which provides a communication with the slide-valve chamber when the control-valve 15 is in position to close the passage 16 to said chamber.

The horizontally-disposed engine 4 is fitted only with the slide-valve chamber 10', similar to the valve-chamber 10 of the vertically-disposed engine. In this chamber 10' 5 may be supported to be seated a slide-valve similar to the slide-valve 11 and adapted to operate the engine in the same manner. There need be no control-chamber similar to 14 in connection with the horizontally-disposed engine, for its hammer does not need the interposition of such control to define its position when at rest, and it may therefore be operated directly from the initial control.

15 Referring now to Fig. 5 in connection with Fig. 1, 22 is the valve-casing of the initial or foot control. As seen in Fig. 1, this control is placed in such position relatively to the machine that it may be operated by the foot 20 conveniently. In this casing 22 is a rocking valve 23, which is rocked by a shaft 24 grooved into it, as shown in Fig. 7. This shaft 24 extends outwardly through the casing 22 and is mounted in walls 25 of the base- 25 plate 26, which carries the casing. Fixed to the rock-shaft 24 between the bearing-walls 25 is the pedal-casting 27, the upper surface of which is formed with or has secured to it a foot-rest 28, so disposed, as seen in Fig. 5, as 30 to enable the operator by pressure of the toe or heel to rock the shaft 24 in either direction. The pedal-casting 27 has a foot-stem 29, which fits and is packed in a seat 30 in the base-plate 26. With this seat, under the 35 packed stem 29, a passage 31 communicates, said passage communicating at its other end with a port 32, open at its upper end to a groove 33 in the valve 23, so that the pressure in the valve-casing 22 is admitted under 40 the pedal-casting to hold it steady in a neutral or middle position against any unintentional pressure while the foot is resting on the pedal or against accidental displacement of any kind. The valve 23 is provided with 45 a central groove 34, which, as seen in Fig. 7, is open when the valve is in neutral position to the side ports 35 and 36 in the casing 22 and also is open to the intervening relief-port 37.

The port 36 of the initial casing 22 is connected, as shown in Fig. 1, by a pipe 38 with the valve-chamber 10' of the horizontally-disposed engine 4. The port 35 of said initial casing is connected by a pipe 39 with the upper end of the control-chamber 14 of the 55 vertically-disposed engine 6, said pipe opening into said chamber, as shown in Fig. 2, above or back of the piston 18.

In the initial casing 22 is a top passage 40, Figs. 6 and 7, to which is fitted a T-coupling 60 42, (shown in Fig. 1,) the near branch of which may be regarded as the inlet to the system for the fluid under compression and with the other branch of which is connected a pipe 41, which leads up to and opens into

the side of the control-chamber 14 of the vertically-disposed engine 6, as is seen clearly in Fig. 3.

The operation is as follows: The position of the initial foot-controlled valve 23 shown in Fig. 7 is the neutral one, in which both engines are at rest. It will be seen that the port 36 is closed by the valve to the pressure-space in the casing above said valve, and therefore there is no pressure in pipe 38, leading to the horizontally-disposed engine 4, 75 and said engine is inoperative. It will also be seen that said pressure-space in casing 22 is open through pipe 41 to the control-chamber 14 of the vertically-disposed engine 6, and therefore the pressure is upon the front 80 of the piston 18 in said chamber. Now as the port 35 of the initial casing is closed by the valve 23 to the pressure there is no pressure in the pipe 39 to the back of said piston, and it follows that the pressure from 85 pipe 41 in front of said piston will have forced said piston over or up to its limit, as seen in Fig. 2, thereby causing the control-valve 15 to cover the passage 16 to the valve-chamber 10 of the engine, so that no pressure is admitted to said chamber to operate the engine. Moreover, in this position of the control-valve 15 the contact-arm 19 of its stem 17 bears, as seen in Fig. 2, on the holding-pin 20, which in turn bears on the slide-valve 11 and holds it inoperative over to one limit, thereby exposing one of the engine-ports. A small amount of the pressure fluid passes through the small port 15' in the control-valve 15 and through the slide-valve 90 chamber and enters the engine-cylinder through its exposed port, thereby holding its piston up with its hammer retracted. Any resistant pressure in either engine is relieved in the position shown in Fig. 7 through 100 the ports 36 and 35, the groove 34, and the relief-port 37. When the horizontal engine 4 is to be operated, pressure is exerted upon the toe of the pedal-casting 27, whereby the valve 23 is so rocked as to open the port 36 to the pressure-space, whereupon the fluid passes through the pipe 38 to operate the horizontal engine in the ordinary manner. In this movement it will be observed that the connections to the vertical engine are not affected, and said engine remains inactive. To operate the vertical engine, pressure is placed on the heel of the foot-casting in such manner as to rock valve 23 to close port 36 115 and to open port 35 to the pressure-space. The pressure now passes through the pipe 39 to the top or end of the control-chamber 14, back or on top of the piston 18. The pressure area back of this piston being greater than the pressure area in front of it, the 120 valve 15 is thereby moved over to uncover the passage 16 to the slide-valve chamber and to cause the arm 19 to release its pres- 125

sure on the sliding holding-pin 20. In this position the valve 15 is held, and the pressure is admitted to the engine-valve 11, which is now free to operate. When the operator releases the pressure of his foot, the fluid-pressure from above the valve 23 passes through the groove 33, port 32, and passage 31 to the packed stem 29 of the pedal-casting and holds said casting steady in its neutral position.

Having thus described my invention, what I claim as new, and desire to secure by Letters Patent, is—

1. In a machine having a plurality of independent fluid-engines, the combination of a lever, an initial valve operated by the lever for controlling fluid-pressure, and means operated by said pressure for separately controlling said fluid-engines.

2. In a machine having a plurality of independent fluid-engines, the combination of a lever, a valve operated by the lever for controlling fluid-pressure, and means operated by said pressure for separately controlling said fluid-engines, said means including a fluid-controlled valve for admitting and cutting off the pressure to the engine valve-chamber.

3. In a machine having a plurality of independent fluid-engines, the combination of a lever, a valve operated by the lever for controlling fluid-pressure, and means operated by said pressure for separately controlling said fluid-engines, said means including a fluid-controlled valve for admitting and cutting off the pressure to the engine-valve chamber, and contact devices between said control-valve and the engine-valve to arrest and to release said engine-valve.

4. In a machine having a plurality of independent fluid-engines, the combination of a lever, a valve operated by the lever for controlling fluid-pressure, and means operated by said pressure for separately controlling said fluid-engines, said means including a fluid-controlled valve for admitting and cutting off the pressure to the engine - valve chamber, said control-valve having a small port through it to admit pressure to one end of the engine-cylinder to hold its piston retracted when the engine is at rest, and contact devices between said control-valve and the engine-valve to arrest and to release said engine-valve.

5. The combination with a plurality of independent hammer-driving fluid-engines, of fluid-operated means, including an initial pressure-controlling valve, for separately controlling each engine, and a lever for operating said initial valve.

6. In a machine having a plurality of independent fluid-engines, a fluid-operated means for separately controlling each engine, said means involving a fluid-control valve which

admits and cuts off the pressure to and from the engine-valve, and contact devices between said control-valve and the engine-valve for throwing the latter into and out of operation.

7. In a machine having a plurality of independent fluid-engines, a fluid-operated means for separately controlling each engine, said means involving a fluid-control valve which admits and cuts off the pressure to and from the engine-valve, and contact devices between said control-valve and the engine-valve for throwing the latter into and out of operation, said contact devices consisting of a projecting stem of the control-valve, a contact-arm of said stem, and a slidable holding-pin impinging against said arm and engine-valve.

8. In a machine having plural independent fluid-engines, one engine being set vertically and the other horizontally, the combination of a control-chamber for the vertically-disposed engine communicating with the valve-chamber thereof, a valve in said control-chamber controlling said communication, contact devices by which said control-valve throws the engine-valve into and out of action, a rocking lever, and fluid-operated means operated by the lever to actuate the control-valve of the vertical engine and to independently operate the horizontal engine.

9. In a machine having plural independent fluid-engines, one engine being set vertically and the other horizontally, the combination of a control-chamber for the vertical engine communicating with the valve-chamber thereof, a valve in said chamber controlling said communication, contact devices by which said control-valve throws the engine-valve into and out of operation, a rocking lever and fluid-operated means operated by the lever to actuate the control-valve of the vertical engine and to independently operate the horizontal engine, said means comprising fluid-passages to the engines, and an initial pressure-controlling valve operated by the lever and controlling said passages.

10. In a machine having plural independent fluid-engines, one engine being vertically and the other horizontally disposed, the combination of a fluid-control chamber for the vertical engine communicating with the valve-chamber thereof, a valve in the said control-chamber controlling said communication, means by which the movement of said valve throws into and out of action the engine-valve, an initial casing with fluid-passages therefrom to each engine to separately operate them, a valve in said initial casing controlling said passages, and a lever for operating said valve.

11. In a machine having a plurality of independent fluid - engines, fluid - operated means for separately controlling each engine,

said means including an initial valve-casing, passages therefrom to the engines, a valve in said casing controlling said passages, a rocking lever for operating said valve, and fluid 5 communications from said initial casing controlled by said valve, for holding said lever in neutral position.

In testimony whereof I have signed my name to this specification in the presence of two subscribing witnesses.
